READING GLASS

Emmett G. Forgea, Fort Sill, Okla.

Application December 17, 1937, Serial No. 180,452

2 Claims. (Cl. 88—39)

(Granted under the act of March 3, 1883, as
amended April 30, 1928; 370 O. G. 757)

This invention described herein may be manufactured and used by or for the Government for governmental purposes, without the payment to me of any royalty thereon.

5 This invention relates to a reading glass, more particularly it is directed to a device of this character including magnifying means and having means for illuminating objects such as maps or the like to be magnified.

10 The principal object of the invention is to provide a relatively inexpensive and at the same time an efficient and convenient type of reading glass.

Other objects of the invention are to provide a 15 reading glass having means to support the same at the proper distance from the magnified object, to properly light a portion of a map or other object to be magnified, to provide a lighting unit having a source of current supply from dry cells, to provide means for detachably connecting the 20 lighting unit to the supporting means of the reading glass, and to provide means for permitting use of a plotting scale, rule or writing implement within the device on the magnified and illuminated portion of the map or the like.

25 With the above and other objects and advantages in view the invention consists of certain features of construction and operation of parts which will hereinafter appear and in which—

30 Fig. 1 is a top view of the invention;

Fig. 2 is a vertical sectional view taken on the line 2—2 of Fig. 1, and

Fig. 3 is a side view thereof.

In the illustrated embodiment characterizing the invention, a body portion 1 is provided which 35 may be made of tin or other suitable material having the property of diffusing light impinging thereon, or the interior of the body may be lined or coated with light diffusing material such as 40 aluminum paint or the like. The body portion 1 is opened at its lower or bottom end 2 and closed on its upper end by a lens 3 mounted in a holder 4. Intermediate the upper and lower ends of 45 the body portion at substantially the central portion thereof is a lateral opening 5 in which a bezel portion 6 of a flashlight 7 is adapted to project. The flashlight 7 is of a flat substantially oblong shape having rounded ends 8. The bezel portion 6 is formed on one side of the flashlight 50 at the center thereof and is adapted to surround a lens 9 which closes the outer end of a reflector 10, the inner end of the reflector 10 being adapted to surround the base of an electric lamp 11, which is energized by means of dry cells 12 and 55 controlled by a switch button 13 in the conven-

tional manner. The longer portion of the oblong shaped flashlight 7 is vertically mounted on the body portion 1 and is detachably held to the body portion by means of a U-shaped member 14, the free ends 15 of which are pivotally connected to 5 opposite sides of the body portion by rivets 16 or the like. The outer portion 17 of the U-shaped member extends out from the body portion 1 a sufficient distance to pass over the upper end 8 of the flashlight and contact the outer side 18 10 thereof. The side of the body portion 1 containing the lateral opening 5 is shaped to present a flat surface 19 against which the inner flat side of the flashlight 7 may abut, the upper end of the flat surface 19 terminating in a curved surface 15 20 which conforms to a portion of the curvature of the upper rounded end 8 of the flashlight.

A substantially U-shaped re-entrant cut-out portion 21 is formed in the lower end of the body portion 1 at a right angle to the lateral 20 opening 5 for a purpose which will hereinafter appear.

In using the device, the flashlight 7 is placed on the body portion 1 adjacent to the lateral opening 5 and the U-shaped member 14 is turned 25 on its pivots 16 to engage the upper end of the flashlight. The open bottom 2 of the body portion 1 is then placed on a portion of a map or the like to be illuminated and magnified and the switch button 13 is manipulated by the hand to 30 operate the lamp 11 through the dry cells 12. A plotting scale, rule or writing implement may then be inserted within the body portion 1 by means of the cut-out portion 21 provided therein and used on the magnified and illuminated portion of the map or other object.

Even though I have herein described the invention as a reading glass, it is nevertheless to be understood that it is not limited to a glass for reading printed matter only, but may be used as 40 a magnifying glass for all purposes, such as reading printed matter, examining material of various sorts, used by surgeons and others to illuminate parts of a person's anatomy and the like.

It is obvious that various changes may be made 45 in the form and construction of the device without departing from the spirit and scope of the invention.

Having described my invention, what I claim as new and wish to secure by Letters Patent is:

50 1. A light conserving magnifier comprising a casing having an internal light reflecting surface and a lateral opening, one end of said casing constituting a magnifying lens, the other end of said casing being open and having a peripheral edge 55

lying in a plane, which peripheral edge is adapted to seat on a surface to be examined, means constituting a light source contiguous to said lateral opening, said light source adapted to project light rays through said opening onto the internal light reflecting surface of said casing and another lateral opening in said casing constituting a window through which an indicator may be inserted, said last mentioned lateral opening extending through said peripheral edge.

5. A light conserving magnifier comprising a casing having an internal light reflecting surface and a lateral opening, one end of said casing constituting a magnifying lens, the other end of said

casing being open and having a peripheral edge lying in a plane, which peripheral edge is adapted to seat on a surface to be examined, a lamp housing abutting said casing and extending from said lateral opening, a lamp in said housing, said lamp adapted to project light rays through said opening onto the internal light reflecting surface of said casing, another lateral opening in said casing constituting a window through which an indicator may be inserted and means pivotally connected to said casing and adapted to engage detachably said lamp housing for holding said housing against said casing.

EMMETT G. FORGEA.
